UNITED STATES PATENT OFFICE.

HORACE EVERETT, OF PHILADELPHIA, PENNSYLVANIA.

DESIGN FOR A SHEET-METAL CAN.

Specification forming part of Design No. 5,808, dated April 23, 1872.

Specification describing a Design for a Sheet-Metal Can, produced or invented by HORACE EVERETT, of Philadelphia, Pennsylvania.

The figure in the accompanying drawing represents a side view of a sheet-metal can made in accordance with my design.

The body of the can is cylindrical, with a flat top and bottom, and it is provided in the present instance with a detachable lid, *a*, and a hinged bail, *b*.

The design consists of a scalloped or waved bead or beads, *d*, formed upon and extending around the body of the can, as clearly illustrated in the drawing. These beads are in the present instance arranged between and adjacent to plain beads *e e*, which extend around

the body of the can, at points close to the top and bottom of the same; but the said plain beads form no portion of my design, and may be dispensed with.

I claim—

The design for a sheet-metal can, having formed upon it a scalloped or waved bead or beads, substantially as described, and as represented in and by the accompanying drawing.

In testimony whereof I have signed my name to this specification in the presence of two subscribing witnesses.

HORACE EVERETT.
